UNITED STATES PATENT OFFICE.

PATRICK F. WHALEN AND PATRICK J. BURKE, OF PORTLAND, OREGON.

SHIRT-FOLDING TABLE.

1,125,785.

Specification of Letters Patent.

Patented Jan. 19, 1915.

Application filed March 17, 1914. Serial No. 825,432.

To all whom it may concern:

Be it known that we, PATRICK F. WHALEN and PATRICK J. BURKE, citizens of the United States, residing at Portland, in the county of Multnomah and State of Oregon, have invented certain new and useful Improvements in Shirt-Folding Tables, of which the following is a specification.

Our invention relates to an improvement in shirt-folding tables, and has for its object to provide a device of the kind indicated, which is adapted to receive the body of a shirt and act as a form for folding the shirt after ironing.

15 A further object is to provide such a table which is equipped with a form which can be readily adjusted to suit the size of the shirt in hand.

We accomplish these objects by means of 20 the structure shown in the accompanying drawing, in which—

Figure 1 is a top plan view of our complete device, showing a folded shirt thereon. Fig. 2 is an edge view of same. Fig. 3 is 25 a bottom plan view of Fig. 1.

Describing the drawing in detail, 1 represents a section of the usual laundry table which is provided with two pairs of oppositely disposed transverse slots 3 which are 30 spaced apart a distance required by the dimensions of a folded shirt. Each plate is provided with a facing plate 2, one of which, at each side is provided with a scale 4. A guide rail 6 which is preferably of a 35 length corresponding to the length of the largest sized shirt when folded, is secured upon each longitudinal pair of plates, by means of bolts 5 each passing through a slot 3.

40 7 represents the usual card board placed upon the body of a shirt which has been folded upon our improved table. The rails having first been adjusted laterally in the slots 3 to the width the shirt will occupy 45 when folded, the shirt will be placed with the front downward and neck band 8 will be adjusted within the recess 15 of the table to prevent it being crushed, the collar button fitting within the recess 17. The

sleeves and lower portion of the shirt will 50 now be folded upon the card board, and adjusted to fill the space between the rails. Each of the sides 9 will then be folded in turn from the point limited by its respective rail. This gives a perfect form and a neat 55 finish to the folded article. The rails are simultaneously adjustable by means of the longitudinal bar 12 on the bottom of the table, intermediate each pair of longitudinal slots 3, which bar is slidably held in place 60 in the keepers 10. Upon the lower portion of each bolt 5 is pivoted a bar 11 which inclines rearwardly toward the longitudinal bar 12, each front and rear pair being pivotally secured to said bar 12 upon a pin 16. 65

At the front end of bar 12 is formed a hand hold 14, by means of which the bar may be moved rearwardly to draw the rails toward each other, and by pulling the bar 12 to the front the rails will be separated; 70 and when the proper adjustment of the rails has been obtained the said bar 12 will be secured in fixed position, by means of the set screw 13, thereby holding the rails 6 from movement in their slots. 75

The device is adapted for use in shirt factories and in laundries. By its use, the shirt can be neatly and regularly folded, without the need of measurements or the use of tools or mechanical appliances. 80

We have thus produced an article which is economical in construction, neat in appearance and of great utility in the arts where it is employed.

What we claim as new and desire to secure by Letters Patent, is—

1. A shirt folding table comprising a table proper having a neck-band-receiving recess formed therein, and a guide rail secured lengthwise at each side of said recess 90 constituting a form in which to fold the shirt.

2. A shirt-folding table comprising a table proper having a neck-band-receiving recess formed therein, transverse slide-ways 95 at each side contiguous to said recess and guide rails adjustably secured in said slide ways.

3. A shirt-folding table comprising a table proper having a neck-band-receiving recess formed therein, transverse slide-ways at each side contiguous to said recess, guide rails adjustably secured in said slide ways and manually operated means for adjusting the guide rails.

In testimony whereof, we affix our signatures in the presence of two witnesses.

PATRICK F. WHALEN.
PATRICK J. BURKE.
